MOBILE DENTAL CONSOLE

Richard A. Slouka, Carpentersville, Ill., assignor to American Hospital Supply Corporation, Evanston,
Ill., a corporation of Illinois

Filed Dec. 19, 1968, Ser. No. 15,054

Term of patent 14 years

Int. Cl. D24—03

U.S. Cl. D24—1

FIG. 1

FIG. 2

FIG. 6

FIG. 7

FIG. 9

FIG. 8

FIG. 1 is a perspective view of a mobile dental console embodying the design of my invention;

FIG. 2 is a side elevational view;

FIG. 3 is a top plan view;

FIG. 4 is a front elevational view;

FIG. 5 is a rear elevational view;

FIG. 6 is a perspective view showing the console of FIG. 1 with its top cover removed;

FIG. 7 is a top plan view of the console with its cover removed;

FIGS. 8 and 9 are fragmentary rear and side elevational views of the console with its cover removed.

The parts shown in the drawings in broken lines are for illustrative purposes only.

I claim:

The ornamental design for a mobile dental console, substantially as shown and described.
